UNITED STATES PATENT OFFICE.

MAHLON D. MILLER, OF ST. PAUL, MINNESOTA, ASSIGNOR TO THE UNITED STATES FLAX FIBRE COMPANY, OF NEW JERSEY.

METHOD OF AND APPARATUS FOR CLEANING WASTE TOW.

SPECIFICATION forming part of Letters Patent No. 599,342, dated February 22, 1898.

Application filed February 19, 1896. Serial No. 579,966. (No model.)

To all whom it may concern:

Be it known that I, MAHLON D. MILLER, a citizen of the United States of America, residing at St. Paul, in the county of Ramsey and State of Minnesota, have invented certain Improvements in Methods of and Apparatus for Cleaning Waste Tow, of which the following is a specification.

My invention relates to the art of cleaning and working flax fiber, its object being to produce an improved process of and apparatus for cleaning the short-fibered waste tow, as well as the short fiber of flax-plants grown for the purpose of producing seed only and which is practically entirely a waste product, preparatory to carding and spinning the same. The tangled mass of this tow is filled with shive or portions of the woody fiber of the plant, to which the tow fiber tightly clings, so that it cannot be shaken out.

It is necessary to bear in mind that my invention is preliminary to, but wholly independent of and different and distinct from, the process of carding. It merely serves to pare the fiber for carding, which operation is then carried out in the same manner and to like extent as with clean fiber which has not been subjected to treatment by my invention. It is also to be borne in mind that the material to be treated has always heretofore been a waste product to be disposed of by burning or to a limited extent utilized at a merely nominal price in lieu of packing material, such as excelsior or hay or in paper-manufacturing. The material in question is of too short fiber to be practically treated by machinery or methods heretofore known. It is the refuse material combed out of and thrown off from the long fiber or line-stock in the process of manufacturing the latter, and carries with it the shive which has been freed from the line-stock.

The quantities of this waste product annually produced are enormous and all efforts to save and utilize it have heretofore entirely failed, although the fiber itself when cleaned is for many purposes equal or even superior to the long fiber. The material being itself the waste combed out of the long fiber, it cannot

be itself cleaned by like machinery or processes, but other means must be employed to separate the shive from the fiber. By means of my invention I successfully and perfectly accomplish this end, so that when the process is completed the material may be delivered directly from my machine to the carding-machine wholly free of foreign matter, while the fibers may be in as confused and tangled a mass as before treatment, to be straightened and laid by the card in condition for spinning. Any long fibers in the mass are also broken in two in the operation, so that all are of sufficiently uniform length to be successfully worked.

The gist of my invention consists in so subjecting the confused and uncombed mass to the influence of centrifugal force as to throw out of and away from it the shive which is thereby entirely separated therefrom or is detached while so thrown out by other means. To subject all portions of the mass to the efficient influence of centrifugal action, it is necessary to bring them all to the exterior of the mass, where no fiber can confine and restrain the shive. It is also important to thoroughly stir and disintegrate the mass to assist in detaching the fiber from the shive and permit it to be thrown out. The amount of applied centrifugal force should also be gradually increased as the cleaning proceeds, the heavier or larger particles being first thrown off and the speed finally attained being sufficient to remove even the lightest and smallest particles.

For the carrying out or working of my process I prefer to employ a series of toothed cylinders rotated oppositely adjacent each other and at progressively increasing peripheral speeds. The material is thus carried upon these cylinders, alternately over and under the same, according to their direction of rotation. Each cylinder as it rotates at higher speed than its predecessor seizes and draws the material off from the teeth of the latter, separating and subdividing it and reversing its surface exposure. Preferably above each alternate cylinder over which the material is carried I arrange a toothed roll which pene-

trates the mass and picks and loosens it as it passes. Also underneath the cylinders under which the material is carried I arrange abutments or stops, preferably with crimped 5 or serrated edges, which stand close to but without penetrating the material upon the cylinders and against which are whopped off the particles of shive which are projected beyond the cylinder, but are held from dislodgment by the clinging fiber. The construction, arrangement, and operation of the machine will more clearly appear from the following detailed description of the specification and the accompanying drawings, forming 10 part thereof, in which—

Figure 1 shows a side elevation of my improved apparatus, parts of the frame thereof being broken away the better to show the construction of the machine. Fig. 2 is a plan 15 view of the same. Fig. 3 is a detail showing the manner of connecting the stops to the frame underneath the cylinder. Figs. 4 and 5 are details of a serrated stop; Figs. 6 and 7, similar details of a crimped stop, and Figs. 20 8 and 9 of a straight-edged stop.

In the drawings, A represents the frame or base of the machine, supporting in suitable bearings the series of cylinders 2, 3, 4, 5, 6, and 7. These cylinders are graded progressively, their diameters increasing from the receiving or feeding end of the machine to the delivery end, so that when they are driven at a uniform rotative speed their peripheries have progressively greater velocities. The 25 cylinders are clothed with suitable wire teeth, either straight or inclined in the direction of rotation. The cylinders are rotated oppositely, as indicated by the arrows, by the following-described means. The driving-shaft 9 is driven by means of the pulley 10 by a belt connected with the source of power. This shaft carries another pulley 11, over which runs the belt 12, thence it runs over the pulley 13 of the shaft 14 of the cylinder 45 5, thence under the pulley 15 on the shaft 16 of the cylinder 6, and thence over the pulley 17 on the shaft 18 of the cylinder 7, whereby, the pulleys being of the same size, the shafts are rotated oppositely at uniform speeds. 50 On the other end of the shaft 9 is a pulley 19, connected by means of the crossed belt 20 with a similar pulley 21 on the shaft 22. Upon the shaft 22 is also mounted the pulley 23, which serves to drive the belt 24, running 55 over the pulley 25 on the shaft 26 of the cylinder 2, thence under the pulley 27 on the shaft 28 of the cylinder 3, and thence over the pulley 29 on the shaft 30 of the cylinder 4, the pulleys being of such size that the 60 shaft speed of all of the cylinders 2 to 7, inclusive, is substantially the same.

Adjacent to the cylinder 2 are the rolls 31 and 32, and above the roll 32 the clearing-roll 33, these all being clothed with suitable teeth. 65 The roll 31 is driven from the shaft 22 by means of the crossed belt 34, running over the pul-

ley 35 on the shaft 22 and the pulley 36 on the shaft of the roll 31. The rolls 32 and 33 are then driven from the roll 31 by means of the belt 37. The endless feed-belt 38, running over rolls 39 and 40, is driven from the roll 39, which in turn is driven by means of the belt 41, running over the pulley 42 on the shaft 22 and the similar pulley 43 on the shaft of the roll 39. 75

Above each of the odd-numbered cylinders 3, 5, and 7 is arranged a toothed roll 44, supported in suitable bearings upon standards 45. These rolls are driven by means of crossed belts 46, running over pulleys upon the 80 shafts of the cylinders. At the rear or delivery end of the machine is arranged the clearer comb or brush 47, carried by the arms 48, 49, and 50, which are connected to the rock-shaft 51. The shaft is oscillated or 85 rocked by means of the pitman 52 from the crank 53, actuated by the pitman or link connection 54 with the pulley 55, which is driven from the shaft of the cylinder 7 by means of the belt 56. 90

58 is a chute or inclined table upon which the material cleared from the cylinder 7 drops and is carried from the machine.

Arranged underneath and parallel with each of the even-numbered cylinders is the 95 cross-bar 59, upon the sides of which are secured stops 60, and similarly under the odd-numbered cylinders are arranged cross-bars 61, carrying a single stop 62. These stops may be of any suitable construction and are 100 set close enough to the teeth of the cylinder to be struck by the shive, which is protected from the mass of tow by centrifugal force, but clings to the fibers, whereby the shive is whopped off or torn from the tow. In some 105 cases I prefer to use the form of stops shown in Figs. 4 and 5, having a beveled or serrated edge, in other cases the form shown in Figs. 6 and 7, and in still other cases an entirely straight edge, as shown in Figs. 7 and 8. For 110 ordinary purposes the most useful forms are the serrated and crimped edges.

In operation the tow is delivered in a thin layer over the feed-belt 28, between the feed-rolls 31 and 32, onto the downwardly-rotating 115 cylinder 2. Thence it passes half-way around the cylinder until cleared from it by the oppositely-rotating cylinder 3, which picks it off and carries it upward and underneath the toothed roll 44, which loosens and stirs it still 120 more. From this cylinder it is taken by the cylinder 4, and so on through the series. Each cylinder has a greater peripheral speed than the preceding, and the teeth of the former consequently strike into the mass of tow on 125 the other and pull it off therefrom. In so doing the tow is separated and disintegrated and is reversed in position upon the receiving-cylinder, whereby the under surface of the layer on one cylinder becomes the outer 130 surface on the next, and in the progress of the mass through the machine all portions

at some time are brought to the surface, so that the centrifugal action upon the shive is unrestrained by any superimposed fiber. Every particle of foreign matter is thus thrown out of and separated from the tow by centrifugal force, or if adhering to the fibers is whipped off by the stops against which it strikes as carried around by the ballooning fiber of the mass. The pulling off of the tow by one cylinder from the other also serves to break up any long fibers and reduce all to substantially uniform length. The function of the stirring-rolls is to assist by their loosening of the mass the detaching and freeing of foreign matter which does not so tenaciously adhere to the fiber as to require to be whipped off by the stops, but will be thrown out by centrifugal force alone. The number of cylinders and their degree of speed are such as to thoroughly clean the fiber, which is finally cleared off from the last cylinder by the comb or brush 47 and delivered to the chute in a confused and tangled mass to be afterward carded.

25 I claim—

1. The method of cleaning a mass of tow, which consists in subjecting it to the action of centrifugal force, and simultaneously picking and loosening the same.

30 2. The method of freeing a mass of tow from shive and other foreign matter, which consists in subjecting it to the action of centrifugal force progressively increasing.

35 3. The method of freeing tow from foreign matter of greater specific gravity than its fiber, which consists of subjecting a mass of it to the action of centrifugal force, simultaneously picking and loosening the same, and successively separating it apart and reversing its surface exposure until the entire mass has been thus exposed.

40 4. The method of separating foreign matter from a mass of tow, which consists of subjecting it to the action of progressively-increasing centrifugal force simultaneously stirring and loosening the mass, and successively with each increase of applied centrifugal force, reversing its surface exposure.

45 5. The method of freeing a mass of tow from shive and other impurities which consists in subjecting it to the action of centrifugal force to throw such impurities outward, and simultaneously removing the impurities adhering to its fiber.

50 6. The method of cleaning tow, consisting of subjecting it to the unrestrained action of centrifugal force to throw the intermingled impurities out of and away therefrom, picking and loosening the mass of tow, and detaching such impurities as are thrown away from the mass but adhere to its fibers.

65 7. The method of cleaning a mass of tow of its impurities, consisting of subjecting it to the action of centrifugal force, simultaneously picking and loosening it to release the

included impurities, successively separating the mass apart and reversing its exposure, and progressively increasing the applied centrifugal force, whereby heavier impurities are first thrown off, and then the lighter, and all of the mass is brought to the surface to free its entangled impurities.

8. The method of cleaning a mass of tow, consisting of subjecting it to the action of centrifugal force to throw off the heavier impurities, picking and loosening the mass while under the influence of such force, successively separating and rearranging the mass to bring the interior portions to the exterior, progressively increasing the applied centrifugal force and detaching from the mass the impurities projected therefrom but clinging to its fibers.

9. Means for separating foreign matter from a mass of tow by centrifugal force, comprising a series of toothed cylinders, means for rotating them oppositely with progressively-increasing peripheral speed, intermediate devices for picking and loosening the mass, and the stops for whipping off the impurities projected outward but clinging to the tow fibers.

10. Means for separating impurities from tow by centrifugal force, consisting of a series of contiguous cylinders, means for rotating them oppositely at progressively-increasing peripheral speeds, and the clothing of teeth upon said cylinders inclined in the direction of their rotation adapted to gather the tow from those of the preceding cylinder, and thereby expose all the portions of the mass and permit the impurities in the same to be thrown out of and away therefrom.

11. Means for cleaning tow by centrifugal force, consisting of a series of adjacent cylinders, means for rotating them oppositely at progressively-increasing peripheral speeds, said cylinders having clothing of teeth inclined in the direction of their rotation adapted to gather the tow from the teeth of the preceding cylinder, and deliver it to those of the succeeding cylinder, and the stops for detaching the matter which is thrown away from the cylinders but clings to the fibers of said tow.

12. Means for cleaning tow, comprising in combination a series of horizontally-arranged contiguous cylinders, means for rotating them oppositely at progressively-increased speeds, the wire-toothed clothing upon said cylinders inclined in the direction of their rotation, adapted to clear the tow from the teeth of the preceding cylinder, and to be cleared of said tow by the teeth of the succeeding cylinder, the crimped or serrated stops arranged closely adjacent to said cylinders, and in the path of foreign matter attached to fibers of said tow but thrown away from the surface of the same by centrifugal force, and the toothed stirring-rolls arranged adjacent to said cylinders and adapted to penetrate into and stir and loosen the mass of tow thereon.

13. Means for separating impurities from
tow by centrifugal force, consisting of a series
of contiguous cylinders, means for rotating
them oppositely, at progressively-increasing
5 peripheral speeds, and the clothing of teeth
upon each of said cylinders, adapted to pick
and loosen the tow and gather it from the
preceding cylinder and thereby expose all

portions of the mass and permit the impuri-
ties to be thrown out of and away therefrom. to

In testimony whereof I affix my signature
in presence of two witnesses.
